UNITED STATES PATENT OFFICE.

HIRAM K. WHITNER, OF CHICAGO, ILLINOIS.

SAFETY-SUPPORT FOR WINDOW-CLEANERS.

SPECIFICATION forming part of Letters Patent No. 606,400, dated June 28, 1898.

Application filed February 2, 1898. Serial No. 668,815. (No model.)

To all whom it may concern:

Be it known that I, HIRAM K. WHITNER, a citizen of the United States, residing at Chicago, in the county of Cook and State of Illinois, have invented certain new and useful Improvements in Safety-Supports for Window-Cleaners; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates more particularly to improvements in safety-supports for window-cleaners. In addition to the customary stay, strap, or rope used in connection with a safety-belt worn upon the person of the window-cleaner, I have used a supplemental rope guard in a manner that necessitated the duplication of the so-called "permanent fixtures" and "stay-terminals" well known to those skilled in the art to which the service appertains. Such method was tolerated only when the work to be done was exceedingly hazardous and in which the additional cumbersomeness was warranted by the exigencies in such exceptional cases, but such method did not warrant a general introduction of said supplemental rope in the service.

The object of my invention is to not only support window-cleaners in their perilous positions more securely than heretofore, but by means hereinafter shown I facilitate their work by overcoming the objectionable features that heretofore obtained when introducing into said safety apparatus a supplemental guard.

My invention consists in a reserve guard of novel construction and suspended from the appurtenances of a safety jacket or belt without duplicating the stay-terminals common to said safety jacket or belt and without limiting the movements of said window-cleaners in their avocation while outside of the window.

Figure 1 is a view in perspective of a portion of my safety-jacket the subject of Patent No. 519,365, issued to me May 8, 1894, and embodying my invention. Fig. 2 is an enlarged representation of my improved guard-carrier shown detached from Figs. 1 and 4.

Fig. 3 is an enlarged representation of my improved combination-eye shown detached from Figs. 1 and 4. Fig. 4 is a view in perspective of a portion of my safety-belt the subject of Patent No. 559,472, issued to me May 5, 1896, and embodying my invention.

In Fig. 1, A represents a belt well known as a "safety-jacket." Said jacket may be of the usual construction and preferably connected with stay C and my guard D by means of a combination-eye held in positions 1 and 2 by rivets $e'f'$ and e^2f^2 . G and H are parts of the well-known terminals to safety-stay C, heretofore in use and described in the above-cited patents, said stay C being connected to terminal G or its equivalent by any of the approved methods heretofore used, preferably through the intervening hitch g. Said stay C is now rove through stayway k' in carrier K, also rove through stay-eye E' and E², Fig. 1, also rove through eye h of terminal H or its equivalent. Said stay C is fixedly lashed or clamped about the thimble h' of eye h, preferably by means of wrappings h² and h³ and S-hooks h⁴ and h⁵, closed about said wrappings. The prolongation of stay C in D constitutes my improved guard, which latter is now rove through guard-eye F² and F', Fig. 1, successively and then rove through guard-way k² in carrier K, the free end d of said guard D being formed into a dead-eye d', omitting the customary thimble usually placed in such positions. A metal thimble in this position might endanger the glass of windows.

In Fig. 2 I show a method I preferably use in constructing my new and novel carrier K. A piece of leather of suitable dimensions is folded with the end k⁴ upon the end k³, said lappings being held in position by rivets k⁵ and k⁶, thus forming stayway k' and guard-way k², the end k³ projecting into stayway k'. Said end I preferably serrate, thus forming a serrated tongue k', as shown in Fig. 2, whereby said carrier K may the better be retarded in its movements along stay C. It will not be a departure from the spirit of my invention to use a carrier having but a single way, through which both stay C and guard D may be roved.

In Fig. 3 I show a detached enlarged view of my combination-eye E and F, preferably

used for securing said stay C and guard D to my safety-jacket A, Fig. 1, or my belt B, Fig. 4, or their equivalents. In said combination-eye the stay - eye E is placed uppermost, 5 through which the (working) stay C is rove, as shown in Figs. 1 and 4, the guard-eye F being placed below, through which the (reserve) guard D is rove, as shown in Figs. 1 and 4, (said eyes when designated in Fig. 1 10 have their position 1 and 2 added,) in order that any slack in said guard D may fall away from stay C, thereby preventing any fouling of stay C. Inasmuch as guard D is not held absolutely taut, said guard-eye F in 15 the combination-eye may be of the ordinary simple construction. Not so with the stay-eye E in said combination-eye. Here I not only provide an antifriction-surface on each side of the base of said combination-eye E 20 and F and designate them M and N, but when said surfaces are broadened out they not only reduce the wear of stay C to a minimum, but they also prevent a rocking of said combination-eye, (shown in use in Figs. 1 and 4,) which 25 rocking would be harmful to both stay C and guard D. Rivet-holes e and f, placed in the projecting ends of said combination-eye, complete the construction of my improved combination-eye. It would not be a departure 30 from the spirit of my invention to construct Fig. 3 with but a single eye large enough to receive both stay C and guard D and thus take the place of the combination-eyes in Figs. 1 and 4 or their equivalents. However, 35 a single eye in place of the combination-eye E and F for both stay C and guard D and a single carrier-way, above referred to, would not be attended with the best results. The wear on the (reserve) guard D 40 must be kept at a nominal nothing. At the same time carrier K, when properly constructed on lines above suggested, will hold guard D taut enough to keep said guard D practically parallel with and close to said stay 45 C, thus keeping both stay and guard on the right-hand side of the window-cleaner practically in position of the one stay heretofore used, making said duplication unobjectionable from a hindrance standpoint in his work. 50 Another important feature is attained by using a carrier in the manner carrier K has proven its efficiency since put into service in connection with an indispensable practice for safety—that is, placing terminal H or 55 its equivalents in engagement with its permanent window-fixture before the window-cleaner emerges from the building through the open window after placing terminal G or its equivalent in like manner. The window-cleaner may lay hold of both stay C and guard D with one hand and grasp carrier K with the other hand, pulling said stay and guard through said carrier K, in order that stay C may be adjustably shortened to the proper 60 width of a narrow window to be cleaned by means of the hitch g, while the pendent free end d of said guard D may hang as surplus 65

rope. Now when the cleaner goes to a wider window after placing terminal H or its equivalent, as before, said cleaner has simply to 70 move over to the opposite side of the wider window. The combination-eye in position E' and F', Fig. 1, or combination-eye in position X, Fig. 4, hereinafter described, will contact with carrier K, forcing it out of the limit required for lateral movements in cleaning said wider window, where said carrier K will be held by its bite upon stay C, and by its bite upon guard D the latter will be held practically taut while the window-cleaner moves 80 from side to side of the window in cleaning said window after terminal G or its equivalent has been placed and the adjustment of stay C has been made as heretofore. 85

In Fig. 4 I show how to place the combination-eye E and F in position of X Y Z or their equivalents for holding stay C and guard D upon belt B in order that the best results may be obtained as a belt-sling (described in Patent No. 559,472) when the said duplication is applied to the said form of belt. It will be obvious that in any event and with any manner of belt should stay C break the fall would be arrested by guard D pulling on terminal H or its equivalent. Should the window-cleaner lose his footing before he placed the terminal G or its equivalent, which has happened in a number of instances during a practice of six years, then the fall will be checked by the (shorter) guard D. Should 95 the latter break, then the window-cleaner would drop to the limit of the (longer) stay C. Hence in introducing the duplication into belt-sling B, Fig. 4, it is important that both stay C and guard D be so rove that in case 100 of either breaking the remaining acts upon said belt B independently of the leather-buckling feature O O O, which latter (as in any form of belt that is held upon the person of a window-cleaner by means of buckles) is the 105 weakest part of said belt B and shown in Fig. 4. In other words, that no strain be brought upon said buckling feature shown in Fig. 4 and more fully shown in Patent No. 559,472. Another very important feature is that the 110 stay-eye and the guard-eye in the combination-eye in the position of E' and F' in Fig. 1 and X in Fig. 4 be on the same plane relative to the contacting end of carrier K in order that said combination-eye may force said carrier beyond the limit of the side movements of said window-cleaner without turning the one or the other of said ropes (designated stay C and guard D) back over the edge of its specially-provided eye in positions E' and F', Fig. 1, or position X, Fig. 4, and thereby inflicting injury in said stay or guard, as the case 115 may be. 120

I preferably make guard D a continuation of stay C in order that when said stay C is 125 worn to the danger-point (it being the working rope) and requires renewal then guard D should be renewed also, even though worn but very little. Should stay C and guard D

be spliced independently into terminal eye *h* or its equivalent, guard *D* might be made to serve the time of several stays, thus bringing both stay *C* and guard *D* finally to the danger-point, thus defeating the purposes of my invention.

I am aware that it is not new to introduce a second rope or stay into a belt for the purpose of additional safety and therewith duplicate the terminals and permanent fixtures. Such an arrangement would make the safety apparatus too cumbersome to admit of its general introduction into the service, or if one end of an extra rope or guard be attached to the belt direct the slack obstructs the window-cleaner in the performance of his work. Again, should the extra guard be fastened to both terminals in the manner of a single rope or secured to the stay proper by means of buckles or their equivalent on the ends of said extra guard then the wear on both, if not alike, would be at least alternate and the fundamental principles of my invention would not be attained, nor would the adjustment of said extra guard be automatic in its adaptation to wider windows.

What I claim as new and novel in my invention is providing a non-working reserve in a guard that is self-adjusting to the limit required in cleaning windows of different widths after an adjustment has been made in the working stay in use heretofore and in the usual manner and holding said reserve guard practically taut in a manner not obstructive to the window-cleaner in his avocation and not liable to excessive wear.

Having thus fully described my invention, I will now in claims point out what is new and novel—

1. In a safety apparatus adapted to encircle a person, the combination with a stay and its terminals, of a guard fixed to one of said terminals and means whereby said guard is held in relative position with said stay, substantially as and for the purpose set forth.

2. In a safety apparatus adapted to encircle a person, the combination with a stay and its terminals, of a guard fixed to one of said terminals, a combination-eye fixed in said safety apparatus and means whereby said guard is held in relative position with said stay, substantially as and for the purpose set forth.

3. In a safety apparatus adapted to encircle a person, the combination with a stay and its terminals, of a guard fixed to one of said terminals, a carrier movably attached to said stay whereby said guard is held taut, and means whereby said guard is held in relative position to said stay in said safety apparatus, substantially as and for the purpose set forth.

4. In a safety apparatus adapted to encircle a person, the combination with a stay and its terminals, of a guard fixed to one of said terminals, a combination-eye fixed in said safety apparatus, and a carrier movably at-

tached to said stay and said guard whereby said guard is held adjustable in relative position to said stay in said safety apparatus, substantially as and for the purpose set forth.

5. In a safety apparatus adapted to encircle a person, the combination with a stay and its terminals *G* and *H*, of a guard *D* fixed to terminal *H* and means whereby guard *D* is held in relative position to stay *C*, substantially as and for the purpose set forth.

6. In a safety apparatus adapted to encircle a person, the combination with stay *C* and its terminals, of a guard *D* fixed to one of said terminals, a combination-eye fixed in position *E'*, *F'* and in position *E²*, *F²* in said safety apparatus and means whereby guard *D* is held in relative position to stay *C*, substantially as and for the purpose set forth.

7. In a safety apparatus adapted to encircle a person, the combination with stay *C* and its terminals, of a guard *D* fixed to one of said terminals, a carrier *K* movably attached to stay *C* and guard *D* and means whereby guard *D* is held in relative position with stay *C* in said safety apparatus, substantially as and for the purpose set forth.

8. In a safety apparatus for window-cleaners, the combination with stay *C* and its terminals *G* and *H*, of a guard *D* fixed to terminal *H*, combination-eyes fixed in positions *E'*, *F'* and *E²*, *F²* in safety-jacket *A*, carrier *K* movably attached to stay *C* and guard *D*, substantially as and for the purpose set forth.

9. In a safety apparatus adapted to encircle a person, the combination with stay *C* and its terminals, of a guard *D* fixed to one of said terminals, a carrier *K* having a guard-way *k²* and a stayway *k'* provided with a serrated tongue *k"* and means whereby said guard *D* is held in relative position with stay *C* in said safety apparatus, substantially as and for the purpose set forth.

10. In a safety apparatus adapted to encircle a person, the combination with stay *C* and its terminals, of a guard *D* fixed to one of said terminals, a combination-eye having a stay-eye *E* and a guard-eye *F* provided with antifriction-surfaces *M* and *N* and rivet-holes *e* and *f* as a means whereby said guard is held in relative position with stay *C* in said safety apparatus, substantially as and for the purpose set forth.

11. In a safety apparatus for window-cleaners, the combination with stay *C* and its terminals *G* and *H*, of a guard *D* fixed to terminal *H*, a combination-eye fixed in positions *X*, *Y* and *Z* in belt *B*, carrier *K* movably attached to stay *C* and guard *D*, substantially as and for the purpose set forth.

In testimony whereof I affix my signature in presence of two witnesses.

HIRAM K. WHITNER.
